11 Claims. (Cl. 234—5.4)

The invention relates to a device for determining the numerical value of a measurement, and more particularly to a measuring device for weighing scales. In this device, the measurement readings are subdivided according to orders of magnitude, e. g., units, tens, hundreds, etc., and are determined by means of mechanical feeler devices, which cooperate with stepped segments, hereafter termed leaflets, after the measuring instrument has adjusted itself into the position of equilibrium. For example, when the measuring instrument is actuated, the stepped leaflets are caused to move back and forth past the mechanical feelers until the parts of the instrument are in equilibrium. Then the feelers are moved into engagement with the adjacent stepped leaflets to thereby determine the reading.

The device according to the invention is of much simpler construction as compared to known types of such devices, requires a substantially smaller amount of space, and is also substantially less expensive to manufacture than those heretofore known. Another advantage of the apparatus forming the subject of the invention also consists in the fact that those parts of the device which are connected with the measuring instrument are of small size and of very light weight, whereby the load on the instrument shaft is very substantially reduced. Another advantage may be recognized in the fact that provision has been made to prevent the possibility of any incorrect result being ascertained owing to any external influence being exercised on the device.

Owing to a yielding connection between the measuring instrument and the member on which the feelers are to be operated, any damage being suffered by the device or by the measuring instrument owing to mishandling is excluded.

Further, according to the invention, the figures for all orders of magnitude are determined from the same edge of the leaflet on which the feelers are to be operated, which circumstance enables the device to be constructed so as to be of great simplicity, while at the same time accuracy can even be increased, as the precise adjustment of a single leaflet edge will assure accuracy for all orders of magnitude.

Owing to its small requirements of space, the device can be mounted on the scale side of the head of weighing scales, while at the same time this arrangement does not prevent indication by means of a pointer.

On the accompanying drawings, an embodiment shown by way of example of the device according to the invention, as applied to weighing

scales, is shown in a diagrammatical manner, although it is obvious that this device can also be employed in connection with other measuring instruments.

40 Fig. 14 is a sectional view illustrating the mounting of the device on the head of a weighing scales;

Fig. 15 is an exploded isometric view showing the coaction between the feelers and stepped leaflets;

45 Fig. 16 is a face view of each of the leaflets employed.

Figs. 1, 1A, 2 and 3 show a disc 1 flexibly connected with the shaft of the weighing scales, said disc having small leaflets 2 inserted therein. In order to reduce the load on the instrument shaft and/or the gyroscopic moment of the moved parts, the disc 1 is preferably made of light metal, whereas the members carrying the set of steps, e. g., the leaflets 2, are made of resisting material,

i. e., of steel. As appears from the drawing, the periphery of this disc 1 is divided into a certain number of equal divisions and slotted in radial directions. Into each radial slot, there is inserted a thin leaflet 2, preferably made of spring steel, and fastened into position. Each of these leaflets are notched as at 3, thus forming legs 4 (Fig. 3) and when the leaflets are inserted into the slots of the disc 1, the legs 4 will project inwardly in radial directions from the slots, and on opposed sides of the disc, so as to prevent any possibility of their becoming shifted in an axial direction. In order to fasten the leaflet 2 in position, as shown on Fig. 2, a hole 5 is provided within the range of the periphery of the disc 1. After inserting the leaflets, the adjacent material of the disc 1 is pushed into hole 5 by means of a pointed caulking tool and thereby the leaflets are secured against any displacement in a radial direction.

In the case of the arrangement shown in front elevation, plan view and side elevation in Fig. 3, two flaps 6 are cut out from leaflets 2 in the vicinity of the periphery of the disc 1, which flaps are, after the leaflets have been inserted into the slots of the disc, bent from the position shown in full lines, into the dotted line position, e. g., to engage grooves in the disc.

Figs. 4 and 5 represent an elastically yielding coupling between the disc 1 and a shaft 8 actuated by the weighing scales, which coupling enables the shaft to continue its deflection, while the disc 1 is held fast. To the end of the shaft 8 is fixed a sleeve 10 and an associated disc 11. On this sleeve, a hub 12 of a casing 13 is rotatably supported, said casing having feeler disc 1 secured thereto. A collar 15 secures the disc 1, casing 13, and the hub 12 against any axial displacement away from disc 11. Hub 12 is loosely mounted on sleeve 10. From the disc 11, there projects a pin 16, while from the casing 13 and disc 1, there projects a pin 17. Impact plates 18 and 19 are supported in a rotatable manner on the hub 12 of the casing 13, said plates having outstanding legs which engage opposite sides of the pins. A spiral spring 20 normally urges the outstanding legs of the two impact plates against the pins 16 and 17, and a sleeve 14 prevents axial displacement of the impact plates 18, 19.

In case the shaft 8 is rotated, this motion is transmitted by means of disc 11, pin 16, plate 18, spring 20, plate 19 and pin 17 to the disc 1 and the latter is thereby rotated. If the disc 1 is held fast during the rotation of shaft 8, the spring 20 will be compressed, and owing to the special construction of the spring, the shaft may rotate through an angle of approximately 270° relative to the disc before stopping. If the disc 1 is released again, the spring 20 will again return exactly to its normal position relative to the shaft 8 and the disc 1. The pins 16 and 17 are held securely in their position of rest by the tension of the spring. It is thus seen that considerable flexibility is present in the driving connection between shaft 8 and disc 1.

In the following, we shall, by way of example, describe the feeler device for a weighing scales having a weighing range of 2,000 kg. and an accuracy of indication of 1/1,000th of the maximum load. In this case, the external edges of the leaflets 2 in the feeler disc 1 are spaced from each other at a peripheral distance of 50 units of indication to form a division. Since each unit represents two kg., each division between the leaflets will represent 50 times two, or 100 kg. In

the case of a thousand units of indication, this division must accordingly repeat itself on the periphery of the feeler disc twenty times. In order to ensure that the zero figure and the maximum figure on the scale, and accordingly also on the feeler disc, should not coincide, the periphery of the disc is preferably divided into 21 parts (see Fig. 1A), so that one division between the zero and the maximum value will not be utilized to represent units of indication. The leaflets 2 separated by the 21st division will correspond to the zero value and to the maximum value, respectively. The above-mentioned twenty-one leaflets 2 are differently notched, and are therefore designated by the letters *a* through *u*. In Fig. 16, the face views of these leaflets are shown. Figs. 6-9 represent the feelers for the feeler device disclosed. In the case of an accuracy of 1/1,000th of the maximum load, 0 or 10, 2, 4, 6, 8, . . . kg. should be indicated in the lowest order of magnitude. For each order of magnitudes, e. g., units, tens, hundreds, etc., one feeler should be provided. The feelers for the various orders of magnitude are T-shaped and have substantially the same general dimensions, said feelers having toothed racks 23 on the legs thereof to enable them to be driven. In the upper edge of the feeler 22 for units (Fig. 6), ten teeth 24 are provided alongside each other and each tooth has five steps therein. Each step corresponds to one unit, i. e., two kg. of indication for figures repeating themselves, there being a total of five times two, or ten kg., represented by the horizontal width of each tooth. For example, the five steps in each tooth successively represent 0 or 10, 2, 4, 6 and 8 kg., so that fifty units in all are marked on the ten teeth in the upper edge of the feeler. Thus, it is seen that the width of feeler 22 represents the same number of units as the center to center distance between leaflets 2 on the disc 1; consequently, the width of feelers 22 must be equal to the center to center distance between adjacent leaflets 2.

Fig. 7 represents a correcting feeler 27, the width of which is exactly the same as that of the other feelers, and which carries on its upper edge a pointed tooth system 26 comprising fifty teeth. Its leg is of greater length than that of the other feelers, the purpose of this arrangement being explained further below. In the leg of this feeler, an oblong hole 28 is provided into which a peg 29 projects from the adjacent feeler 22 for units.

Fig. 8 represents the feeler 30 for tens which on its upper edge has ten steps 31 which are preferably arranged in a direction opposite to that of the steps in the feeler for single figures (Fig. 15).

Fig. 9 represents a feeler 32, the upper edge of which is, in contradiction to those mentioned before, made straight-lined. Such a feeler is employed for the orders of magnitude of hundreds, as well as for those of thousands.

These feelers are for the purpose of establishing a figure corresponding to the weight of the article or substance being weighed. When establishing this figure, the feelers cooperate with the leaflets 2 of the disc 1, said feelers being mounted one beside the other in a common casing 33 in such a manner that their lateral and front surfaces are situated exactly in the same planes (Fig. 10). At the same time, the feelers are arranged parallel to each other in the casing and can be driven independently of each other by means of their tooth systems 23 and by corre-

sponding gear wheels 21. The upper edges of the feelers are arranged in a radial position relative to the axis of rotation of disc 1, and the plane of each feeler is disposed substantially at right angles to the plane of the engaging leaflets 2 (Figs. 1A, 10 and 10A). The feelers are moved during the process of their operation towards the disc 1, i. e., towards the leaflets 2. Owing to the arrangement described of the feelers, each feeler 27, 22, 30 and 32 will make impact against the same leaflet 2 during operation. In the limiting case in which the centre lines of two adjacent leaflets 2 are situated exactly opposite lateral edges of the feelers as shown in Figs. 6 and 7, the feelers will move against the same two leaflets but in such a case the correcting feeler 27 will slightly rotate disc 1 until only one leaflet engages the feelers.

The correcting feeler 27 is of a slightly greater length than the others. In the position of rest, feeler 27 is guided by the peg 29 extending from the feeler 22, representing units. Under the action of the spring 34 (Fig. 10) engaging directly the bottom edge of feeler 27, the feeler 27 is supported on the lower edge of the oblong hole 28, in such a position that the tooth system of feeler 27 will project above the plane of the other feelers. In consequence thereof, when the feelers are operated, it is first the correcting feeler 27 which will come into contact with a leaflet 2 and will bring the disc 1 into such a position as to ensure that a leaflet 2 should always make impact against the middle portion of a step of the unit feeler 22. The units feeler 22 and the tens feeler 30 cooperate with the upper edges 2a of all leaflets 2, said edges 2a being situated at the same radial distance from shaft 8 and, in consequence thereof, the adjustment of the figures ascertained by means of the feelers in these orders of magnitude will be effected in accordance with the necessary movement of a feeler until a step makes impact against a leaflet 2. No steps are provided on the feelers 32 for hundreds and thousands; however, the leaflets 2, which cooperate with these feelers 32, are fitted with steps 2b and 2c.

In view of the fact that the distance between two adjacent leaflets 2 corresponds to fifty units of indication, corresponding to 100 kg., each leaflet will be notched at the place 2b cooperating with the hundreds feelers (Fig. 16), so as to be of greater depth, corresponding to one step depth of preceding leaflets, from 0 to 9 in succession. Accordingly, this stepping of the leaflets is repeated twice along the whole periphery. For example, the notches 2b (Fig. 16) progressively increase in depths from leaflets a through j, and from leaflets k through t.

As the division on the feeler disc corresponds to 100 kg., each group of ten leaflets for the determination of the thousands figures will possess the same height at the respective cooperating places. Accordingly, the first ten leaflets a through j (Fig. 16) remain maintained in the original height at edge 2c, the next ten, k through t will be made lower by one step along edge 2c and the twenty-first one, i. e., u, will be made lower by two steps along the edge 2c.

In the case of the type of construction described, the periphery of the feeler disc has been divided into twenty spaces representing units of indication plus an additional space heretofore described, that is to say, twenty-one parts. It would, however, also be possible to divide the periphery into ten parts. The division into ten parts would apparently have the advantage that

a smaller number of leaflets 2 would have to be accommodated on the feeler disc. The drawbacks connected with this arrangement are, however, preponderate, as, firstly, the feelers would in that case have to be made double the width of the feelers disclosed. In the case of a width of feeler corresponding to a 36° disc arc, the movement of the feeler, when a leaflet stops in the center of the feeler and when a leaflet stops near the end of the feeler, will cause appreciable differences in the results. In other words, with the leaflets spaced 36° apart, it would accordingly no longer be possible to make the top surfaces of the feelers straightlined. Instead, the top surfaces would have to be made arcuate and at the same time the various steps would have to be made of different width. Moreover, the mass of the feelers and consequently the moment of acceleration during their rapid movement would affect the operation to a greater extent.

Figs. 10 and 11 represent the whole feeler and control device in front and side elevation. The feelers are, as previously mentioned, located within a casing 33 fixed on the base plate 35. The tooth portions 23 of the various feelers engage four gear wheels 21, which are fixed on four concentric shafts 36 mounted one within the other (Fig. 10A). The other end of each of these shafts has an arm 37 fixed thereon. On each shaft 36 a gear wheel 38 is loosely mounted, which wheel drives the figure roll 40 through the transmission wheel 39. Each gear wheel 38 is provided with a pawl tooth system 41 which is engaged by a pawl 44 fixed on the end of an arm 43, said arm being pivoted as at 42. This pawl reaches over all the four gear wheels 38, in such a manner that it holds fast all the four wheels when engaging the same. One part of the periphery of the gear wheel 38 is cut away to provide a support for one end of a spiral spring 45, which spring has its other end supported on the arm 37. This arm, under the action of the spring 45 is urged against a stop 46 of the adjacent gear wheel 38. These springs are shown in Figs. 10A and 11. On the solid internal shaft of the set of concentric shafts 36, there is loosely mounted behind the arms 37 a further arm 48 which has an axial extension 49 integral therewith and projecting in front of the four gear wheels 38. Each arm 37 is subject to the force of an individual spring 50, which at one end engages a fixed stop 51, while the other end is hooked into an arm 37. The spring 50 normally tends to rotate the arms 37 in a counterclockwise direction in Fig. 11 and at the same time force them against the extension 49 of the arm 48. On the lower end of the arm 48, a pin 52 is provided upon which one leg of a bell crank lever 54 rests under the tension of the spring 53. The other leg of lever 54 is engageable with a cam 56 by means of a pin 55, said cam being fixed on the shaft 57. The shaft 57 carries another cam 58, which cam is engaged by a pin 59 on one of the legs of the bell crank lever 43.

In a plate 66 (Figs. 10 and 13), shaft 67 is supported, which shaft carries upon one end thereof a handle 67a. The other end of shaft 67 has an arm 68 secured thereon. On the shaft 67, a hub 69 is loosely mounted, said hub having an arm 70 and a cam 71 extending therefrom. To a pin 70a of the arm 70, a spring 72 is secured, which spring in the case of the rotation of the arm, is tensioned until the pin 70a is rotated about 180°. The pin 70a cooperates with a lug 73 provided on the free end of a crank 74 of

the shaft 57. This lug has a tension spring 75 connected thereto. On the plate 66, a rod 62 is guided which at one end engages on the cam 71 and which with its other end cooperates with one arm 64 of the pressure hammer. The arm 64 is held fast by a pawl 63 which is released by a nose of the arm 74.

In the plate 76, an arm 77 made of tough and thin material, is also pivoted. The free end of arm 77 carries a triangular plate 78, the width of which is greater than the distance between three adjacent leaflets 2 on the feeler disc 1. A pin 79 extends from the right-hand face of plate 35 (Fig. 10), and on this pin a small light-weight pendulum 80 is mounted, the upper end of which is slotted to match a similarly slotted circular counter-weight 81. This counter-weight serves for balancing the lower longer part of the pendulum 80 which is fitted with a triangular aperture 82 (Fig. 12). In this aperture, there is arranged pin 49a projecting from the arm 49 in such a manner that in the position of rest of the pendulum, the pin can be removed from the aperture 82.

The arm 77 passes through an aperture 77a of the base-plate 35 as well as through a slot 85 provided in a slide 84. This slide will, under the pressure of a compression spring 86, rest upon one end of a pivoted lever 87, the other end of which is maintained in engagement with a guided rod 88 by means of a spring 89. The spring 89 also presses the lower end of bar 88 on the cam 71.

The method of operation of the above-described apparatus is as follows:

As soon as the weighing scales has adjusted itself into the position of equilibrium, the handle 67a and the shaft 67 are rotated in the direction indicated by the arrow (Fig. 13). The arm 68 will immediately engage the arm 70 and will accordingly rotate the latter and the cam 71 in opposition to the tension of spring 72. During the rotation of the cam 71, the rod 62 is pressed down and thereby the arm 64 and the hammer 65 are rotated in opposition to a spring, such as 64a, until the pawl 63 drops on the top of the arm 64 to hold the pawl in fixed position. After the shaft 67 has been rotated substantially 180°, the pin 70a will come into contact with the lug 73 of the arm 74. In the case of a slight further rotation beyond 180°, the crank 70 will pass the dead center position, and will from this point onward return automatically in the same direction under the action of the spring 72 into its initial position. The spring 72 is of such strength that during its release it is able to tension the spring 75 as well as all other springs of the apparatus. During this second period of rotation, the handle may be stopped, or it may be moved, but it will not be possible to exert any influence on the operation of the device. In other words, during driving by the crank, the operating energy is being stored and the operation of the device is not influenced. It is only upon the release of the spring 72 that the operation of the apparatus is started. Such a construction serves the purpose of preventing any possibility of wilfully interrupting the process of feeler operation by holding the handle fast in an intermediate position in which the feelers are in contact with the feeler disc.

During the release of the spring 72, the rod 88 is first lifted by means of the cam 71 and in consequence the slide 84 is let down by means of the lever 87. During this motion of the slide

84, the prefeeler 77, 78, previously lifted to a high level, descends until it comes into contact with the internal edge of the leaflets 2 in the disc 1. Should the weighing scales be in a position of rest at this moment it will be possible for the further processes to take place undisturbed as follows:

Simultaneously with the movement of the preliminary feeler 77, 78, the shaft 57 is set into rotation by the cooperation of the lugs 70a and 73 to cause the spring 75 to be tensioned. At the beginning of the rotation of the shaft 57, the lever 43 and the pawl 44 will be lifted by cam 58 from the teeth 41 of the gear wheels 38 against the tension of the spring 61. At this time, clockwise rotation of wheels 38 (Fig. 11) through springs 45 will be prevented by projections 46 and arms 37. After a rotation of about 30° of the shaft 57 (Fig. 11) and after the preliminary feeler 77, 78 has made impact against the leaflets 2, the bell crank lever 54 will in accordance with the rotation of the cam 56 be rotated around the pivot 42 against the action of the spring 53, so as to enable the arm 48, 49 to be rotated under the pressure of the arms 37, which arms 37 are urged against arm 49 by springs 50. At the same time, the arms 37 are, on one hand, moving the feelers 27, 22, 30 and 32 through a connection comprising shafts 36 against the feeler disc leaflets 2, and on the other hand the number rolls 40 will be rotated by the gear wheels 38. The rotation of each arm 37 will be effected to such an extent that the feeler driven by that arm makes impact against a leaflet 2. The arm 54 is lifted by the cam 56 to such an extent as to allow each feeler to move upwardly the maximum amount necessary for operation under all conditions. Of course, this maximum movement only occurs when certain positions of the leaflets are assumed.

During this motion, it is the correcting feeler 27 which will first engage the leaflet 2 under the action of the spring 34, and said spring will hold the leaflet in question in stationary position. It is only after the completion of this operation that the other feelers will come into contact with the leaflet.

After the figure rolls 40 have been rotated in accordance with the feeler motions, the follower 59 will reach a recess on the cam 58 and the pawl 44 will, under the action of the pulling force of the corresponding spring 61, catch into the tooth system 41 of the four gear wheels 38 and will thereby bring the figures on the figure rolls 40 into the central position. Notably, it might otherwise happen, owing to the large ratio of transmission between a step height (about 0.3 to 0.4 mm.) and a figure size (3-4 mm.) that in the case of the smallest difference in the height of the steps or of the leaflets the figures would not be in alignment. This correction is rendered possible by the connection between feeler and figure rolls established by the springs 45. Since the adjusted feeler figure has been held fast, the pin 55 will drop from the high side of the cam 56 after a small further rotation of the shaft 57. Also, the arm 54 will be pulled down by the spring 53 against pin 52. Upon the engagement of the pin, the feelers will be returned to initial position by means of members 48, 49, 36 and 37. As the gear wheels 38 are held fast by the pawl 44, this movement will cause the springs 45 to become tensioned. Simultaneously with the drawing-back of the feelers, the nose of the arm 54 will come into engagement with the upper end of pawl 63 to rotate the latter until said upper end jumps off

from the nose. During this rotation the lower end of pawl 63 will release arm 64, and thereby the hammer 65 will be released for upward movement under the effect of a spring 64a.

If, at the beginning of the feeler operation, when the preliminary feeler 71, 78 makes impact against the feeler leaflets 2, the latter are in motion, the preliminary feeler will be oscillated by the leaflets 2 and the arm 71 of the preliminary feeler will swing out the pendulum 80, so that when operating the driving mechanism the pin 49a of the arm 48, which drives the feelers, will be unable to find its way into the slot of the aperture 82 in the lower end of the pendulum 80 (Fig. 12), and this arm will therefore be unable to continue its movement. The feeler operation is accordingly prevented and therefore the wheels 40 will not be rotated. The rest of the procedure can be performed unhindered, only the hammer 64 will engage the wheels 40. Obviously, the wheels may be constructed to print special symbols, e. g., crosses or the like, for indicating an erroneous operation.

If the feeler disc has been in a position of rest at the beginning of the feeler operation and if an impact takes place during the feeler operation, this will not influence the result of feeler operation, as the correcting feeler 27 will hold the feeler disc fixed and the impact will be absorbed exclusively by the yielding coupling (Figs. 4 and 5) provided between the feeler disc and the shaft of the scales.

As appears from the foregoing description, the whole process of feeler operation takes place under the action of tensioned springs in a perfectly automatic manner and within a very short time; for example, within a few tenths of a second. This quick operation is rendered possible by the fact that the mass of the parts moved during the operation of the feelers is extremely small and the paths covered are extremely short, so that the feelers can be operated rapidly, and can be stopped without any substantial shocks.

Up to now, all indicating and printing devices of this kind were mounted at the rear on the head of the weighing scales and in consequence thereof the simultaneous observation of the scale and the operation of the feeler device was hardly possible. The apparatus, according to the invention, only takes up a small amount of room so that it can be fixed without any difficulties on the scale side of the head of the weighing scales. In Fig. 14, the assembly of the apparatus on the scale side of the head of a weighing scales is shown diagrammatically. On the front end of the pointer shaft 8, there is fixed the feeler disc 1 according to the invention, which preferably also carries the pointer 91. The pointer is constructed in such a manner that it is not hindered by the feeler device during this motion. It is not absolutely necessary that the pointer 91 should be fixed on the feeler disc. It may just as well be fixed on the pointer shaft 8 behind the figure disc. It is only necessary that the pointer should not, during its rotation, collide against the feeler and indicating device, this being ensured by the bending shown on the drawings. The pointer 91 moves in front of the scale 92, fixed on a frame 93 of the casing 94. As a certain part remains free on the scale between the zero position and the maximum load, in the example described $\frac{1}{21}$ part of the periphery, in front of which the pointer will never pass, it is possible to use this space for the suspension of the feeler and indicating device. At this place, a block 95 is fixed on the frame 96, the front end

5 of said block supporting the base plate 35 of the whole device. The scale is covered in the usual way by a glass plate 97 which has at its center a sufficiently large aperture for the feeler and indicating device. On this base plate, the cover 98 is fixed, from which the handle projects and in which an opening or a slot is provided for the cards to be inserted.

I claim:

10. In an article weighing instrument, the combination of a toothed member moved by said instrument an amount in direct proportion to the weight of the article, said teeth having variable lengths representing different numerical orders of magnitude, means for arresting said toothed member in stationary position after it has been moved by said instrument, means for sensing said arrested teeth, means controlled by said sensing means for numerically determining said weight, operating means for said sensing means, and means for automatically preventing said numerical determination when said operating means is actuated before the movement of said toothed member ceases.
15. In an article weighing instrument, the combination of a rotary disk driven by said instrument an amount in direct proportion to the weight of said article, a plurality of spaced members carried by said disk, said members having variable lengths which represent different numerical orders of magnitude, a plurality of feelers for sensing one of said spaced members, means controlled by said sensing means for numerically determining said measurement, operating means for said sensing feelers, and means for automatically preventing said numerical determination when said operating means is actuated before the movement of said disk and spaced members ceases.
20. In a measuring instrument having differential members moved thereby, means for selecting one of said members in accordance with the measure taken, said differential members representing different numerical orders of magnitude, a sensing means for engaging said selected differential member, means controlled by said sensing means for numerically determining said measurement, operating means for said sensing means, and means operated by said sensing operating means for stabilizing said differential members before said sensing means engages the selected differential member.
25. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
30. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
35. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
40. In a measuring instrument having differential members moved thereby, means for selecting one of said members in accordance with the measure taken, said differential members representing different numerical orders of magnitude, a sensing means for engaging said selected differential member, means controlled by said sensing means for numerically determining said measurement, operating means for said sensing means, and means operated by said sensing operating means for stabilizing said differential members before said sensing means engages the selected differential member.
45. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
50. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
55. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
60. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
65. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
70. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.
75. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, and means operated by said feeler actuating means for stabilizing said differential members before said feelers move into engaging position.

measurement, operating means for said sensing means, means operated by said sensing operating means for stabilizing said differential members before said sensing means engages the selected differential member, and means for automatically preventing said numerical determination when said sensing means is operated before the differential members are stabilized.

6. In a measuring instrument having differential members moved thereby, means for selecting one of said members in accordance with the measure taken, said differential members representing different numerical orders of magnitude, a plurality of differentially movable sensing feelers for engaging said selected differential member, means controlled by the movement of said feelers for numerically determining said measurement, means for actuating said feelers to cause the same to engage said selected differential member, means operated by said feeler actuating means for stabilizing said differential members before said feelers move into engaging position, and means for automatically preventing said numerical determination when said feelers are actuated before the differential members are stabilized.

7. In a measuring instrument, the combination of differential members moved to and fro by said instrument in accordance with the measurement taken, said differential members representing different numerical orders of magnitude, a flexible driving connection between said differential members and said instrument, said driving connection being yielding in both directions, a sensing means for engaging one of said differential members, means controlled by said sensing means for numerically determining said measurement, and means for automatically preventing said numeri-

cal determination when said sensing means engages a differential member while the differential members are in motion.

8. A combination as set forth in claim 7 in which said differential members comprise a plurality of spaced notched plate members and said sensing means comprise a plurality of movable plates arranged for edgewise engagement substantially at right angles to said notched plates.

10 9. A combination as set forth in claim 7 in which said sensing means and the numerical determining means controlled thereby are actuated by the release of a tensioned spring, the spring being tensioned immediately preceding 15 said sensing operation.

10 10. A combination as set forth in claim 3 in which the operating means for said sensing means includes a rotatable shaft and a spring adapted to be tensioned thereby, said spring being coupled 20 to said shaft during the first half of its rotation and automatically disconnected at the beginning of the second half.

11. In a measuring instrument having differential members moved thereby, means for selecting one of said members in accordance with the measure taken, said differential members representing different numerical orders of magnitude, a plurality of differentially movable sensing feelers for engaging said selected differential member, a number wheel rotated by each of said feelers an amount corresponding to the movement of the feelers, each wheel having a plurality of equally spaced numbers on its periphery, and means for subsequently rotating all of said wheels 30 to effect a corrective movement and aline the numbers on the respective wheels.

SÁNDOR TÓTH.
